UNITED STATES PATENT OFFICE.

FERDINAND E. KAUFFMANN, OF RAHWAY, NEW JERSEY.

HAT-CLIPPING MACHINE.

Application filed November 6, 1920. Serial No. 422,205.

To all whom it may concern:

Be it known that I, FERDINAND E. KAUFFMANN, a citizen of the United States, and a resident of Rahway, county of Union, and 5 State of New Jersey, have invented certain new and useful Improvements in Hat-Clipping Machines, of which the following is a specification.

This invention relates to an improved machine for clipping hats made of velour or similar material, such hats being formerly clipped as a hat body before it was formed with a brim, by passing it through machines that clipped it in flat form, or hand clippers 10 have been slowly passed over the outside of the hat, in which case the degree of finish depended very much on the care or thoroughness with which the operator did the work.

20 The invention is designed to provide a machine which clips the hat body quickly over its entire surface, and is also designed to leave no portion thereof unclipped, the manual operation necessary being only such as 25 will start or stop the machine and inserting or removing the hat.

The invention is designed to provide a machine of this kind in which clipping devices are brought to bear on a hat body which is 30 supported so that it rotates, the parts being constructed so that they are movable relative to each other in order that the clipping devices may traverse the entire surface of the hat. I prefer to arrange the clipping 35 devices so that one of them clips the crown, another the top of the brim and another the bottom of the brim.

The invention is further designed to provide a machine of this kind in which the arrangement of the parts is such that the machine is compact and small, and in which the 40 clippings are carried from the machine, and also to provide for a raising of the nap of the velour or similar fabric so that an even 45 cut is brought about during the clipping operation.

The invention further consists of certain 50 details of construction which will be herein- after more fully described and finally em- bodied in the claims.

The invention is illustrated in the accom- 55 panying drawing, in which Figure 1 is a front view of one form of my improved machine, and Figure 2 is a detail of a portion of the mechanism that swings the hat sup- port. Figure 3 is a side view of the machine

shown in Figure 1. Figure 4 is a top view, somewhat diagrammatic, showing the manner in which the hat is swung so that all its parts come in contact with the clipping de- 60 vice. Figure 5 is a horizontal section of one of the clipping devices with a rotary cutter shown partly in elevation, such section being taken on the line 5—5 in Figure 6. Figure 6 is a section taken on line 6—6 in Figure 5. Figure 7 is a detail section taken on line 7 in Figure 5, and Figure 8 is an elevation of one side of the floor plate of the clipping device.

The machine as illustrated is supported on 70 a table 10 which in turn rests on suitable legs or other supports, which are not shown. The hat supporting part of the machine is constructed to support the hat so that it can rotate, so that it can slide while it is rotating 75 and can also be swung.

The form of structure illustrated com- 80 prises a standard 11 which is arranged with the hub 12 in the bearings 13 on the table so that it can be swung by means to be herein- after more fully described, and has at the 85 top thereof a bearing 14 in which the shaft 15 rotates, the shaft 15 being driven by gears 16 and 17 from a flexible shaft 18 which receives its power from the main shaft 19 by means of the gears 20 and 21. The block 22 is used to hold the hat 23 and is made so as to approximate the shape and size of the 90 crown when it is shaped or taut. Since the hat is formed before it is clipped by this 95 machine, the brim 24 extends transversely or laterally from the hat block, as will be clearly evident from Figures 1 and 3. The bracket 25 is secured to the standard 11, the bracket having on its extremity a bearing 27 for the end of the shaft 15, the shaft being 100 secured by feathers or other means for permitting its sliding longitudinally relative to the gear 16 and also the gear 28, which is in mesh with the gear 29, which gear 29 is on a supplemental shaft with the cam 30, which cam 30 has a groove 33 which receives the roller 31 arranged between the collars 32, one at least of these collars being ar- 105 ranged so that it saddles the top of the cam and is thus prevented from rotating with the shaft 15.

A clipping means is mounted so as to 110 traverse the hat, and in the machine illus- trated comprises suitable clipping devices arranged so that they can be brought to bear on the hat to clip its surface, the pre-

ferred arrangement being to arrange one clipping device 34 so that it operates on the top of the brim 24, that is, the upper surface of the brim, and is adapted to be 5 swung away from said brim and also brought back to the brim by the arm 35 pivoted at 36 and actuated by a cam 37 on the jack shaft 38, this jack shaft being driven from the main shaft by means of 10 the gears 39 and 40.

A similar clipping device 41 is arranged at a place so that it will clip the bottom face of the brim and is mounted on an arm 42 actuated by a cam 43 on the jack shaft 15 38, and a clipping device 44 for the crown is mounted on an arm 45 and is actuated by the cam 46. These clipping devices will be described in detail hereinafter.

The hub 12 of the standard 11 is provided 20 with means for swinging it through an angle of at least ninety degrees, the form shown comprising a crank 47 having a pin 48 and resting in the slot 49 of the bar 50, which bar has a roller 51 on the end of 25 it which is arranged in the slot 52 of the cam 53 on the jack shaft 38. The whole device is operated through suitable belting arranged over the fast pulley 54 and the loose pulley 55. Any suitable stopping 30 and starting means, either manual or automatic, can be installed to regulate the starting and stopping of the machine.

The clipping devices are shown in detail 35 in Figures 5-8 and comprise a casing 56 which has a top plate 57 which has an opening at the top and to which is attached an outlet pipe 58 by suitable means, such as a union connection 59, to which is attached a hose 60 (see Fig. 1), which is attached to any suitable source of suction so 40 that the clippings from the fur are withdrawn and do not float about in the air to the detriment of the health of the operator.

The casing 56 is provided on one end 45 with a bearing 60 for one end of the shaft 61. The other end of the shaft, as at 62, is arranged so that it is supported by a bearing plate 63, which bearing plate is substantially flat and is fastened by screws 64 50 on its rear end and has a bearing 65 for the shaft 61, and has a lug 66 into which the bolt 67 is screwed, the bolt 67 also passing through the bosses 68 of the top plate 57, so that all the parts are securely held 55 together.

The plate 63, with its substantially flat formation, permits the use of the cutter close up to a corner, for instance at the point where the brim is attached to the crown. In addition to this it leaves no 60 marks on the crown of the hat where this side of the cutter bears on it, this form of plate permitting the end of the rotary cutter 69 to extend nearly to the outside edge of 65 the casing.

The shaft 61 is operated by means of a suitable flexible shafting 70 which preferably has its end 71 fastened in the end of the shaft by means of a screw or other fastening placed in the hole 72. A rocking plate 73 has secured to its front end a cutter bar 74, which cutter bar has its front edge 75 adapted to be engaged by the blades of the rotary cutter 69 to clip the material of the hat, and to compensate for wear on the cutter and cutter plate the rocking plate 73 is adjustable in bearings, which bearings in turn are adjustable. For this purpose the rocking plate 73 is provided with bosses 76 on its ends, these being recessed each to receive a ball 77 which permits the boss, and consequently the rocking plate, to rock on the ball, the stem 78 of the ball being supported by a spring 79, the tension of which is adjustable by means of the nut 80 screw-threaded on the stem 78, the lower end of the spring abutting on the bottom 81 of a screw-threaded sleeve 82 having a suitable head or finger-piece 83.

The rocking plate can be designed so that its cutting plate has its cutting edge properly positioned relative to the rotary cutter 69 by means of a strand 84 which extends through the supporting element 83, which can be either a handle or one of the arms 35, 42 or 45, and is provided on its end with a nut 84. On the other end it has a head 85 placed in the post 86 of the rocking plate 73, and a spring 87 holds the rocking plate in its adjusted positions, but with a resilience which makes it possible to give the end of the cutter plate 74 a fine adjustment as to its pressure against the rotary cutter.

I prefer to provide means for roughing up 105 the fur, one means comprising a set of steel or similar spring wires 88 fastened by a strip 89 or by other means to the front of the frame, and a plate 90 extends down from the bottom of the top plate to nearly the bottom of the machine to provide only sufficient opening for the strands of the velour to be clipped.

It will be evident from Figure 6 that the 115 material, as at 91, is closely matted very often and it is sufficiently scraped by the wires 88 to loosen it and to raise it to a considerable extent, as at 92, but the suction of air entering the casing, due to its being exhausted through the pipe 60, causes the velour to stand up, as at 93, so that a substantially even cut is provided over the entire surface of the hat. To insure such suction of air through the opening at the bottom of the casing I provide a plate 94, usually made of spring brass and extending from one side of the frame to the other, which bears against or substantially close to a shoulder 95 on the front part of the rocking plate.

It will be evident that as the cutting edge 75 wears down the rocking plate 73 must be re-adjusted, which can be done by turning the sleeve 80, which is screw-threaded in 5 the casing, and this without altering the pressure of the spring 77, which spring insures at all times a proper and tight seating of the bosses 74 and consequently of the rocking plate in the frame. It will be evident from an inspection of Figures 1 and 10 3 that the flexible shafts 70 and the pipes 60 can be provided with sufficient slack so that the arms 35, 42 and 45 can be swung without affecting the operation of these 15 parts.

The operation of the device is as follows:

When the machine is ready to start, the cams 37, 43 and 46 are in such position as to swing the clipping means down away 20 from the hat, or rather the hat supporting block 22, and then the hat 23 is put in place. As the machine starts these cams operate to swing the clipping devices into position, those embracing the brim having guide 25 plates, as 96, on the clipping device 41, and as 97 on the clipping device 34, these plates being preferably made of brass and having curved ends so as to receive the edge of the brim into the open mouth and then guide 30 it between the cutter plates 74 and each of its guide plates, these guiding plates also acting to hold the brim into position while it is being cut. As these clipping devices take position the hat is rotated by means 35 of the mechanism hereinbefore described for at least one complete rotation, and then the cams 37 and 43 operate to swing the brim clipping devices 34 and 41 away from the hat, since the clipping of the brim is 40 now completed.

The clipping device 44 that is clipping the crown remains in position and the cam 30 now begins to slide the hat backward, since the shaft 15 is pulled backward, and 45 as this backward movement begins the cam 53 operates to swing, through the crank 47, the standard 11 so that the hat slowly assumes the position shown at *a* in Figure 4, that is, it is half way around, having turned 50 about forty-five degrees, the turning point being substantially in line with the center of the clipping device 44, and this continues until the hat arrives at the position shown at *b* in Figure 4, which is at right angles to 55 the position the hat originally was in. As this is clipped the cam 46 acts to swing the clipping device 44 away from the hat and the cam 56 operates to swing the arm 11 back to its normal position and the cam 30 60 acts to push the shaft 15 and the hat that it supports back to its normal position, and the hat can be removed from the machine and another hat substituted for a repetition of the above described steps.

65 It will be understood that minor details

can be altered, and that parts can be differently assembled and proportioned, without departing from the scope of the invention.

I claim:

1. A hat clipping machine comprising a 70 hat support including a block to hold a hat with its crown taut and shaped, a clipping device, and means for moving the parts so that the clipping device traverses the entire crown of the hat.

2. A hat clipping machine comprising a 75 hat support including a block to hold a hat with its crown taut and shaped and its brim extended, a clipping means, means for 80 rotating the block, means for moving the clipping means, and means for actuating the hat support so that the clipping means traverses the crown and both faces of the brim.

3. A hat clipping machine comprising a 85 hat support including a block to hold a hat with its crown taut and shaped, a clipping means, and automatic means for moving the parts so that the clipping means 90 traverses the hat.

4. A hat clipping machine comprising a 95 rotatable hat support including a hat block to hold a hat with its crown shaped and its brim extended, a clipping device for the crown, a clipping device for both faces of the brim, means for moving said devices into and out of contact with the hat, and means for rotating the block and the support so that the clipping devices traverse 100 the hat.

5. A hat clipping machine comprising a 105 rotatable support, a longitudinally slideable hat holding block on said support, means for sliding the block, means for rotating the support, and clipping devices disposed so as to traverse the hat when the support is rotated and the block is slid.

6. A hat clipping machine comprising a 110 rotatable support, a slideable hat holding block on said support, means for rotating the support, means for longitudinally sliding the block, arms swingable toward and from the hat, clipping devices on the arms, and operative connections between the support, the block and the arms to cause the clipping devices to traverse the hat to clip the fur on the entire outside surface of the hat.

7. A hat clipping machine comprising a 115 support, a block on the support for holding a hat, a clipping device bearing on the crown, a clipping device bearing on the top of the brim, a clipping device bearing on the bottom of the brim, and operative connections for moving the parts so that the clipping devices traverse parts of the hat, whereby the whole surface is clipped in one operation.

8. A hat clipping machine comprising a 120 means for supporting a hat so that it is 125

rotatable and slidable, a clipping device bearing on the crown, and means for rotating and sliding the hat so that as it rotates it is slid, and means for swinging the 5 hat support so that all the crown is presented to the clipping device.

9. A clipping device comprising a frame, a shaft in the frame, a rotary cutter mounted on the shaft, a thin bearing plate on one 10 side of the frame, in which frame one end of the rotary shaft is supported, whereby the cutter can be operated on the brim of a hat and closely adjacent to the crown.

10. A clipping device comprising a frame, a shaft in the frame, one wall of the frame being thin and having an inwardly projecting recessed bearing to receive the shaft, and a cutter on the shaft and recessed to receive 15 the bearing.

11. A clipping device comprising a frame having an integral side wall, a thin side wall having a recessed bearing on its inner face, a top plate having an opening for the attachment of an exhaust pipe, the top plate 20 having lugs thereon, a screw passing through the integral wall of the frame and the lugs

of the top plate and being in screw-threaded engagement with the end of the thin side plate, a bearing in the fixed wall, a shaft passing through the bearing and having its end in the recessed bearing of the thin side plate, and a cutter on said shaft, the cutter being recessed to receive the last mentioned bearing.

12. A clipping device comprising a frame, 35 a rotary cutter mounted therein, a rocking plate, a cutter plate fastened to the front of the rocking plate and against which the rotary cutter is adapted to bear to operate, screw-threaded sleeves in the frame, a stem 40 in the sleeves, bearings on the rocking plate, said bearings and the ends of the stems being constructed so that they permit a rocking movement of the rocking plate, a spring 45 abutting on the bottom of each sleeve, and means on each stem for adjusting the tension of the spring.

In testimony that I claim the foregoing, I have hereto set my hand, this 5th day of November, 1920.

FERDINAND E. KAUFFMANN.
